WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE

DISPENSING CONTAINER FOR NESTED ARTICLES

Application filed October 19, 1929. Serial No. 400,849.

The present invention relates to a dispensing container for nested articles such as paper cups of the open mouth type, which are to be withdrawn separately from the container, as needed for use.

The object of the invention is to provide a simple and inexpensive container for receiving a stack of nested cups, or other similar articles, and protecting them from dust and dirt, the container being characterized by the fact that it presents to the user only a small portion of the outermost cup of the stack so that it may be readily withdrawn without the user's fingers coming in contact with any of the other cups in the stack. The container is further characterized by the fact that the weight of the stack of cups therein is sufficient to always present the lowermost cup for removal from the container, thereby making it unnecessary to utilize any weights, springs or moving parts in connection with the container in order to dispense the cups.

Furthermore, the container is adapted to support the stack of cups, or other articles, in such a manner that when the projecting end of the lowermost cup of the stack is taken hold of by the user and withdrawn from the container, the remainder of the stack within the container tends to move in a direction away from the cup being withdrawn, thereby facilitating the separation of the lowermost cup from the stack and practically eliminating the possibility of more than one cup at a time being withdrawn. The above and other advantageous features of the invention will herein-after more fully appear, reference being had to the accompanying drawings, in which—

Fig. 1 is a view in front elevation of a container embodying the invention and illustrating the manner in which the lowermost cup is presented.

Fig. 2 is a view in side elevation of the container shown in Fig. 1.

Fig. 3 is a vertical sectional view along the line 3—3 of Fig. 1 looking in the direction of the arrows.

Fig. 4 is a plan view on an enlarged scale,

looking upwardly at the bottom of the container shown in Fig. 1.

Figs. 5 and 6 are vertical sectional views of a portion of the container shown in Fig. 3 illustrating the manner of withdrawing the lowermost cup of the stack.

Figs. 7, 8 and 9 are horizontal sectional views on an enlarged scale, along the line 7—7 of Fig. 3 illustrating the appearance of a cup at different stages in its withdrawal from the container.

Fig. 10 is a vertical sectional view similar to Fig. 5 showing the container empty and with its front opened to receive a fresh stack of cups.

Fig. 11 is a perspective view of a paper cup of the type which the container is particularly adapted to handle.

Like reference characters refer to like parts in the different figures.

Referring to the drawings, the container comprises an elongated rectangular body 1, closed on all sides except at its lower end where it provides a dispensing slot 2 of a peculiar shape which will be hereinafter fully described. As shown in Fig. 3, the body 1 encloses a stack of nested cups 3 with the wedge-shaped end portion 3a of the lowermost cup of the stack projecting downwardly through the dispensing slot 2, so that the portion 3a may be readily taken hold of by the user when it is desired to remove a cup from the container.

Referring now to Fig. 11, there is shown in perspective a single cup 3 of a type that is best adapted to be dispensed by my improved container, although other cups of this same general type may also be handled. The cup 3 provides an open self-extended mouth, substantially circular, or somewhat elliptical, in form with a downwardly tapering rounded body terminating in a sealed wedge-shaped end portion 3a the intersecting sides of which are slightly flattened so that the cup may be readily seized when this portion projects through the dispensing slot 2, as shown in Fig. 3. The cups 3 are preferably formed of paper possessing the requisite stiffness for the cups to always remain in an extended condition, and ob-

viously cups of this type are readily nested within each other to form a stack, such as is shown in Fig. 3, the weight of which tends to move it downwardly into the dispensing slot 2 of the container which will now be described in detail.

As best shown in Fig. 3, the container comprises a back 4 and parallel side walls 5, and a front 6 and top 7, the latter preferably made as one piece and hinged at 8, so that the front and top may be swung downwardly as indicated in Fig. 10 to permit a stack of cups 3 to be readily positioned in the vertical channel-like structure provided by the back 4 and side walls 5. The container may be conveniently attached to a vertical supporting surface 9 by means of screws 10 extending through the back 4. When the container is closed, as shown in Fig. 2, the flanges 11 carried by the combined front and top provide an effective seal with the side walls 5, so that dust and dirt cannot enter the container. In order to hold the hinged front and top closed, the extremities of the top flanges 11 provide depressions 12 adapted to receive suitable projections 13 pressed out of the side walls 5, engagement between the projections 13 and depressions 12 being such as to frictionally hold the hinged front 6 and top 7 of the container closed.

As best shown in Figs. 1, 3 and 4, the dispensing slot or dispensing passage 2 is defined by converging walls 14 and 15, sloping inwardly and downwardly from the back 4 and front 6, respectively, and by parallel walls 16 coextensive with the side walls 5 of the container proper; consequently the slot 2 is of varying cross section throughout. The walls 14 and 15 are tapered and rounded to conform generally to the tapered rounded body of a cup 3 and since the angle between the walls 14 and 15 is slightly greater than the angle between the front and rear walls of a cup body, the stack of cups tends to center itself in the slot 2 and to force the wedge shaped end portion 3a of the lowermost cup through the narrowed end of the slot 2. It is evident from Fig. 7, that the distance between the side walls 16 of the slot 2 is somewhat greater than the width of the elliptical mouth of the open cup shown, measured along its major axis, or the diameter of a circular mouth cup, shown in dotted lines. Consequently, the stack of cups 3 is free to adjust itself vertically within the container without any tendency to bind.

It will also be noted that the front slot wall 15 is flattened at 17, 17 on opposite sides of its main tapered and rounded portion, while opposite portions of the rear slot wall 14 are curved rearwardly at 18, 18 away from the main rounded portion which 55 engages the wall of the lowermost cup in

the stack. As a result, the lower portion or mouth of the slot 2 presents a generally narrow elliptical form with open ends, as shown in Fig. 4, as contrasted to the wide elliptical form of the upper portion of the approach 70 to the slot 2, and the function of this peculiarly shaped slot, when withdrawing a cup, will presently appear.

When it is desired to remove a cup from the container, the user grasps the projecting wedge-shaped portion 3a of the lowermost cup between the thumb and forefinger, as shown in Fig. 5, and pulls the cup downwardly. Prior to the beginning of the withdrawal movement, the cup appears as shown in Fig. 7, with a wide elliptical, or substantially circular mouth but as the cup is drawn into the narrowing slot 2, to the extent shown in Fig. 5, the mouth of the cup assumes a narrow elliptical form, as the walls 85 of the cup are pressed together, as shown in Fig. 8. Continued downward movement of the cup through the slot 2, as shown in Fig. 6, finally flexes the open rim of the cup into the end spaces between the flattened portions 17 of the front wall 15 and the rearwardly curved portions 18 of the back wall 14, so the rim of the cup then appears as in Fig. 9. It will be evident from Fig. 9 that the cup readily conforms itself to the lower portion of the slot 2, since the distance between the slot walls 16 is considerably greater than the original width of the open elliptical or circular cup mouth measured along its major axis or diameter, as the case may be. Consequently, when the cup is drawn into the slot, the relatively stiff material thereof readily springs out into the open end spaces of the slot on either side of its points of greatest constriction. The 100 cup remains in the form shown in Fig. 9 until it is entirely withdrawn from the slot 2, whereupon the compressed and somewhat deformed wall of the cup tends to spring out to resume its original rounded tapered form with an open self-extended mouth.

It is evident that the deformation of a cup, as it is withdrawn, does not in any way crease the walls of the cup, since the deformation is gradual, due to the peculiar form of the slot 2 and its approach surfaces and due also to the fact that the length of the perimeter of the rim of the slot is equal to or somewhat greater than the length of the perimeter of an open cup mouth, whether it be circular or elliptical.

When the lowermost cup is first seized between the fingers preparatory to being pulled downwardly through the slot 2 with a resulting tendency to press together the somewhat flattened sides of the projecting wedge-shaped end portion 3a, the stack of cups above the cup being withdrawn tends to be elevated slightly, since the lower portion of the stack presents a relatively solid mass 125

possessing enough stiffness to resist flexure by the pressure applied between the fingers. In other words, the stack is actually pinched out of the end of the cup being withdrawn. 5 As a result of this reaction between the cup being withdrawn and the stack, only the lowermost cup is separated from the stack and in fact it is practically impossible to withdraw more than one cup from the 10 container at a time. As the withdrawal of a cup from the dispensing slot 2 progresses, the stack presses downwardly to project the wedge-shaped end portion 3a of the next cup through the mouth of the slot where 15 it can be readily taken hold of by the user, so that the container is always self-feeding.

The number of cups in the container at any time can be observed through one or more openings 19 provided in the front 6 20 and preferably covered by a transparent material to prevent the entrance of dirt and dust into the container and when it is desired to charge the container, the front and top are readily swung down, as indicated in 25 Fig. 10 to permit the insertion of a fresh stack.

In order to facilitate the ready separation of the cups from the stack so that only one will be withdrawn at a time from the 30 container, as described above, it has been found desirable to treat the paper from which the cups are made so that the completed cups will present a relatively slippery surface. One way of obtaining this 35 slippery surface is by carefully waxing the paper stock, although other treatments may be employed in order to obtain the desired slipping effect between the inner surface of the cup which is being withdrawn from 40 the stack and the outer surface of the next cup in the stack.

From the foregoing, it is apparent that by the present invention there is provided an extremely simple and effective container 45 for dispensing nested articles, such as open mouth drinking cups, as they are needed for use. After the container has been charged with fresh stack of cups and closed, the cups are at all times completely protected from dust and dirt with only a portion of the wedge-shaped end of the lowermost cup projecting through the dispensing slot in the container. Consequently, when 50 a cup is withdrawn, the hands of the user 55 do not come into contact with any of the other cups in the stack and a withdrawn cup presents its extended open mouth for use as soon as it clears the end of the dispensing slot of the container.

60 I claim

1. A dispensing container adapted to receive and support a stack of self-distended wedge-shaped articles with the weight of the stack causing the lowermost portion 65 thereof to project outside of the container

through a dispensing passage in the lower end of said container, said passage providing walls integral with the container and having a general form approximating the wedge-shaped body of an article, said 70 article being compressed and elongated along axes at right angles to each other during its withdrawal from the container, and said passage being open at opposite sides into open end-spaces of substantial width 75 forming continuations of said passage, to receive portions of the article as it is compressed during withdrawal from the container without creasing said article.

2. A dispensing device comprising a hollow body for freely receiving a stack of nested open-mouthed articles, said body being partially closed at one end by contracting its walls to provide a dispensing slot, the width of which is substantially less 80 and the length of which is substantially greater than the greatest dimension of the open mouth of one of said articles, with the perimeter of said slot as great as the perimeter of the open mouth of said article and 85 with the ends of said slot of substantial width, to compress and elongate an article along axes at right angles to each other as the article is withdrawn from the container without creasing said article. 90 95
